ATTYS.

UNITED STATES PATENT OFFICE.

CASPER MEHLUM, OF WALTHAM, MASSACHUSETTS.

COLLAPSIBLE MANDREL.

Application filed July 29, 1925. Serial No. 46,919.

To all whom it may concern:

Be it known that I, CASPER MEHLUM, a subject of the King of Norway, residing at Waltham, county of Middlesex, State of Massachusetts, have invented a certain new and useful Improvement in Collapsible Mandrels, of which the following is a specification, reference being had therein to the accompanying drawings.

10 The invention relates to a new and useful improvement in collapsible mandrels and relates especially to mandrels for use in the manufacture of fibre tubes although the device embodying the invention is not intended to be limited to such particular use.

Fibre tubes, particularly hard fibre tubes, are usually formed out of cotton waste which is first formed into a web or sheet and then while wet is wound on a mandrel 20 for a sufficient number of layers or windings to build up a tube of the thickness required. After the tube has been built up to the requisite thickness by successive layers of the web of fibre, it is dried hard. It may 25 be either dried on the mandrel on which it is made or it may be removed from the mandrel on which it is made and slipped on to another mandrel or form on which it is dried.

30 The object of the invention is to provide a collapsible mandrel of simple construction on which the fibre tube may be built up and which may be readily collapsed to remove the tube or to insert into an already formed moist tube and then expanded 35 to hold the tube in shape while it is being dried.

The invention will be fully understood from the following description when taken 40 in connection with the accompanying drawings and the novel features thereof will be pointed out and clearly defined in the claims at the close of this specification.

In the drawings:

45 Fig. 1 is a longitudinal section of a device embodying the invention, the mandrel being in its expanded form.

Fig. 2 is an end view of Fig. 1 viewed from the left.

50 Fig. 3 is a section on the line 3—3, Fig. 1.

Fig. 4 is a section on the line 4—4, Fig. 1.

Fig. 5 is a view similar to Fig. 1, but showing the mandrel in collapsed form.

55 Fig. 6 is a section on the line 6—6, Fig. 1.

The mandrel is preferably formed of soft steel.

The main body portion of the mandrel comprises two semi-cylindrical sector members 11, hinged together at 12. The two members 11, 11 are each somewhat less than 180° so that there is an opening 13 between the side edges 14, 14 of the two members 11, 11 as shown in Fig. 6. This opening is adapted to be closed by a separable sector member 15 to form the complete cylinder 60 when the mandrel is in expanded operative form as shown in Fig. 3. The separable sector member 15 is formed with flanges 16, 16 on the inner periphery at its two side edges which when the said closure member 70 is in closed position engage the inner periphery respectively of the two semi-cylindrical body members 11, 11.

The said closure member 15 is mounted upon a pair of parallel longitudinal bars 75 17, 17 which are spaced slightly apart from each other and receive between them the ends of a plurality of links 18 which are pivotally connected therewith by pivot pins 19. The other ends of said link members 18 are pivotally connected at 20 to lugs 21 secured to the inner periphery of one of the semi-cylindrical body members 11. When the said links 18 are in the position shown in Fig. 1 extending at right angles to the axis of the mandrel they will hold the member 15 in closed position in the slot or opening 13 between the edges 14, 14 of the body members 11, 11. By turning the said link members down into an inclined position, as 80 shown in Fig. 5, the said closure member 15 will be moved down within the hollow space of the mandrel and out of closure position, as shown in Fig. 6, whereupon the two side members 11, 11 may be turned on their 85 hinges so as to bring the edges 14, 14 of said two members 11 nearer together and thereby collapse the mandrel.

Means are provided whereby the said closure member may be operated. The members 17, 17 have extension portions 7 at one end, the left-hand end as viewed in Figs. 1 and 5, which extend somewhat beyond the end of the closure member 15. A pin 23 extends transversely between the said extension portions 7. A pin 24 projects inwardly at right angles from a lug 25 secured to the inner periphery of one of the body members 11. An operating lever 26 shown in dotted lines in Figs. 1, 2 and 5 105 is formed with slots 8, 9 respectively which may be engaged with the said pins 23 and 24.

so that when the lever is turned, as shown in Fig. 5, the rods 17, 17 will be moved toward the left and downward into the position shown in Fig. 5, thereby lowering the closure member 15 into the interior of the mandrel, as shown in Fig. 6, and permitting the collapsing of the members 11, 11 on their hinges. When it is desired to return the mandrel into operative form the lever 10 will be moved back into the vertical position as shown in Fig. 1, thereby closing the mandrel.

What I claim is:

1. A collapsible hollow mandrel comprising two segmental body members hinged together at two adjacent side edges and forming together a semi-cylindrical body somewhat less than a complete hollow cylinder with an open space between their adjacent 20 free edges, a movable segment shaped member adapted to close the said open space, said closure member having a longitudinal rib on its inner periphery, a plurality of links extending transversely across the interior of the mandrel and pivotally connected at one end with said rib member and at the other end with one of said body members, said links being normally at right angles to the axis of the mandrel to maintain 25 the closure member in operative position, said rib and closure member being movable both longitudinally and radially inward, thereby turning the links into an inclined position relative to the axis and moving the closure member out of closure position.

2. A collapsible hollow mandrel comprising two segmental body members hinged together on two adjacent side edges and forming together a semi-cylindrical body 40 somewhat less than a complete hollow cylinder with an open space between their adjacent free edges, a movable segment shaped member adapted to close the said open space, said closure member having a longitudinal rib on its inner periphery, a plurality of links extending diametrically 45 across the interior of the mandrel and piv-

otally connected at one end with said rib member and at the other end with the inner periphery of one of said body members 50 adjacent the hinged edge thereof, said links being normally at right angles to the axis of the mandrel to maintain the closure member in operative position, said rib and closure member being rigidly connected together and movable longitudinally and radially inward, thereby turning the links into an inclined position relative to the axis and moving the closure member out of closure position.

3. A collapsible hollow mandrel comprising two segmental body members hinged together on two adjacent side edges and forming together a semi-cylindrical body somewhat less than a complete hollow cylinder 65 with an open space between their adjacent free edges, a movable segment shaped member adapted to close the said open space, said closure member having a longitudinal rib on its inner periphery, a plurality of 70 links extending diametrically across the interior of the mandrel and pivotally connected at one end with said rib member and at the other end with the inner periphery of one of said body members adjacent the 75 hinged edge thereof, said links being normally at right angles to the axis of the mandrel to maintain the closure member in operative position, said rib and closure member being rigidly connected together and 80 movable longitudinally and radially inward, thereby turning the links into an inclined position relative to the axis and moving the closure member out of closure position, a lug secured to the inner periphery of one of 85 said segmental body members near the outer end thereof and having a pin projecting therefrom, said rib having a laterally projecting pin near the outer end thereof and a lever having slots adapted to engage respectively with said pins to operate the said 90 rib with the attached closure member.

In testimony whereof I affix my signature.

CASPER MEHLUM.
